HAIRBRUSH OR SIMILAR ARTICLE

Joseph W. Mayer, Troy, N. Y., assignor to Johnson & Johnson, a corporation of New Jersey

Application March 12, 1956, Serial No. 40,561

Term of patent 14 years

(Cl. D86—10)

Fig. 1 is a top plan view of a hairbrush or similar article showing my new design;

Fig. 2 is a side elevational view thereof;

Fig. 3 is a left end elevational view thereof;

Fig. 4 is a right end elevational view thereof; and

Figs. 5 and 6 are cross sectional views, respectively, on lines 5—5 and 6—6 of Fig. 2.

The characteristic features of my design are shown by means of full lines in the drawing.

I claim:

The ornamental design for a hairbrush or similar article, substantially as shown and described.
